(57) **CLAIM**

The ornamental design for an electrostatic atomized water particles generating module, as shown and described.

DESCRIPTION

FIG. 1 is a front perspective view of an electrostatic atomized water particles generating module of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof; and,

FIG. 9 is a cross sectional view taken along the line 9-9 of FIG. 3.

The even broken lines shown in FIGS. 1-9 represent unclaimed subject matter forming no part of the claimed design. The dash-dot lines in FIGS. 1-3 represent the boundary lines of the claimed design.
